UNITED STATES PATENT OFFICE.

JAMES E. WALLACE, OF BLACKWELL, OKLAHOMA.

COMBINED HOG SHED AND CHUTE.

No. 896,256.

Specification of Letters Patent.

Patented Aug. 18, 1908.

Application filed February 13, 1908. Serial No. 415,744.

To all whom it may concern:

Be it known that I, JAMES E. WALLACE, a citizen of the United States, residing at Blackwell, in the county of Kay and State of Oklahoma, have invented certain new and useful Improvements in a Combined Hog Shed and Chute; and I do declare the following to be a full, clear, and exact description of the invention, such as will enable others skilled in the art to which it appertains to make and use the same.

My invention relates to a combined hog shed and chute.

The objects of the invention are, first, to provide a substantial, convenient and cheaply constructed chute; second, to form the chute in such a manner that it will be of benefit and will serve other purposes than as a chute when not in use as such; third, to provide a suitable and serviceable shed that can be properly lighted and ventilated and is easily accessible for cleaning; and, fourth, to combine in one both a chute and shed with a minimum of material.

The device is especially adapted for use in connection with railway sheds where the animals are taken off the cars for watering and feeding. In this combination of the device, the shed is located adjacent the tracks so that a gang-way may be conveniently used from the cars to the chute.

With these objects in view, the invention consists of certain novel features of construction, combination and arrangement of parts as will be fully described and particularly pointed out in the appended claims.

In the accompanying drawings, Figure 1 is a top plan view; Fig. 2 is a front elevation of the device with parts broken away; Fig. 3 is a side elevation looking in the direction of the arrow of Fig. 1; Fig. 4 is a longitudinal sectional view with the roof in place; Fig. 5 is a similar sectional view with the roof lowered to form the chute; and Fig. 6 is a transverse sectional view on the line 6—6 of Fig. 5.

Referring more especially to the drawings, 1 represents a suitable inclosure which comprises side walls, 2, front end walls 3, and rear end walls 4, the latter having a less elevation than the former, and the sides 2 tapering from the front walls to the rear walls to give a sufficient slant to the roof hereinafter described, and to prevent excessive rise in the chute when lowered. Extending longitudinally of the inclosure, 1, from the front

end wall, 3, to the rear end walls, 4, is a pair of parallel sleepers, 5, and 6, from the ends of which extend vertical supporting braces, 7 and 8, the former of which is located adjacent the rear end wall 4 and supporting a roof girder, 9, and the latter located adjacent the forward end walls and supporting roof girders, 10. The front wall is provided with a central opening, 11, through which the animals pass going into and out of the shed. Outside of the inclosure and attached to the front walls is a pair of vertically extending beams, 12 and 13, connected at their top by a transverse girder, 14, upon which are supported operating pulleys, 15 and 16. Both of the girders, 12 and 13, are provided with aligned apertures, 18 and 19, to receive a supporting bar, the function of which will be hereinafter described.

Hinged to the rear end wall, 4, by a hinge member, 20, is a longitudinal ridge piece, 21, provided with anti-slipping cleats, 22, on its upper surface, and hinged at each edge of the ridge piece by hinges 22^a are roof sections, 23, and 24. The inner edge of these sections is adapted to lie underneath the ridge piece, and the outer edge is adapted to overlie the side walls 2 of the inclosure. An apertured lug, 25, projects outwardly toward the front from the hinge member 26 to which the roof sections are attached. Journaled on the side of the member 13 in a bearing head 27 is a drum shaft, 28, upon which is secured a ratchet wheel, 29, adapted to be engaged by a pawl, 30, carried by the extension arm, 31, which supports the outer end of the drum shaft. A pair of ropes or chains 31^a are wound upon the drum and extend over the pulleys 15 and 16, and have their outer ends connected to the sides of the roof sections 23 and 24, so as to allow them to be raised thereby. A transverse supporting bar 23 passes through the apertures 18 and 19 on the members 12 and 13, and through the apertured lug, 25, so as to normally hold the ridge piece 21 in roof-supporting position.

When it is desired to use the device for a chute, the crank handle of the drum is rotated and the roof sections turned to vertical. The supporting bar 23 is then removed and the ridge piece and its associated roof sections allowed to drop down as shown in Fig. 5. The roof sections form the sides of the chute, and the members 8 on the opposite sides of the entrance, guide the chute in its movements. To maintain the opening uni-

form in size, I provide a tie member, 35, which bridges the girders 5 and 6 and prevents their spreading. Roof supporting girders 36 extend from the front to the back 5 ends of the shed, vertically disposed above the girders 5 and 6 and hook rods 37 are carried by the roof sections so as to engage eyes 38 in the rear wall 4 for holding a roof in position to act as such.

10 From the foregoing description, taken in connection with the accompanying drawings, the construction and operation of the invention will be readily understood without requiring a more extended explanation.

15 Various changes in the form, proportion and the minor details of construction may be resorted to without departing from the principle or sacrificing any of the advantages of the invention as defined in the appended 20 claims.

Having thus described my invention, what I claim as new and desire to secure by Letters-Patent, is:

1. In a device of the class described, an in- 25 closure, a roof therefor comprising hinged sections and a ridge piece inter-connecting them, and means for turning the roof into a chute.

2. In a device of the class described, an in- 30 closure a roof therefor comprising a center section, a pair of side sections hinged thereto, and means for lowering the roof to form a chute with the sections as sides.

3. In a device of the class described, the combination with an inclosure, of a roof comprising a ridge piece and roof sections connected thereto, and means for raising and lowering said sections, and for lowering the ridge piece at one end whereby it may be utilized as a chute. 35

4. In a device of the class described, the combination with an inclosure, of a cover therefor comprising a ridge piece and sections hinged thereto, means pivotally connecting the ridge piece to the inclosure at one end, 40 means temporarily supporting the other end of the ridge piece, and means for elevating the sections on the ridge piece, and for lowering the ridge piece and sections together to form a chute. 45

5. In a device of the class described, a roof comprising a pair of sections, a supporting center section therefor, means for raising and lowering the roof, and cleats on its surface. 50

6. A roof ridge piece having sections hinged thereto, and means for lowering said ridge piece and sections whereby the ridge piece may be utilized as the gangway of a chute and the sections as sides thereof. 55

In testimony whereof I have hereunto set 60 my hand in presence of two subscribing witnesses.

JAMES E. WALLACE.
